UNITED STATES PATENT OFFICE

JOSEPH J. WOJCIECHOWSKI, OF CUDAHY, WISCONSIN, ASSIGNOR TO A. O. SMITH CORPORATION, OF MILWAUKEE, WISCONSIN, A CORPORATION OF NEW YORK

RAILWAY GRADE CROSSING CONSTRUCTION

Application filed March 28, 1931. Serial No. 525,946.

This invention relates to sheet metal railway grade crossing construction.

One of the objects of the invention is to provide a sheet metal railway crossing for which the supporting ties need not be uniformly spaced part.

Another object is to provide such a crossing which may be readily adapted for employment with rails of different heights.

10 Referring now to the drawings wherein is illustrated a preferred embodiment of the invention,

Figure 1 is an end elevation of a portion of a railway crossing constructed according to the present invention, parts being shown in section for the purpose of clearness;

Fig. 2 is a longitudinal section thereof taken on a plane indicated by the line 2—2 in Fig. 1;

Fig. 3 is a top plan view of Fig. 1, certain parts being omitted, and others shown in section for the purpose of clearness; and

Fig. 4 is a fragmentary perspective view 25 of one of the carrier bars.

Referring now more particularly to the drawings, the reference character 10 indicates one of a pair of rails of a railroad track which are secured to cross ties 11 in any suitable manner. Secured to the cross ties 11 by means of spikes 12 and extending parallel to the rails 10 are carrier bars 13.

The carrier bars 13 are made of sheet metal in the form of channels having upper horizontal web portions 14 and downwardly extending supporting side walls 15. The side walls 15 have their lower edge portions bent inwardly toward each other in a plane parallel to the upper web 14 to form flanges 16 which constitute means for providing substantial bearing surface for the carrier members and also to serve as means for securing the same in position.

45 In securing the carrier bars 13 to the cross ties 11, the spikes 12 are passed through aligned holes 17 and 18 in the web portion 14 and bearing flanges 16, respectively, and driven into the cross ties 11. This manner of securing the carrier bars to the ties prevents spreading of the side walls thereof dur-

ing passage of heavy loads over the crossing.

The carrier bars are provided with pairs of ears 20 which are struck up from the upper web thereof at predetermined intervals to provide means for securing tie bars 21 thereto. The tie bars 21 are also made of sheet metal in the form of channels and have upper horizontal web portions 22 and downwardly extending side walls 23. The side walls 23 have their lower edge portions bent inwardly toward each other in a plane parallel to the upper web 22 to form flanges 24 which provide substantial bearing surfaces for the tie bars and also serve as means for securing the same in position on the carrier bars.

The inturned flanges 24 of the tie bars are adapted to underlie the pairs of struck up ears 20 of the carrier bars to maintain the tie bars in adjusted position. The bearing flanges 24 of the tie bars 21 have notches 25 cut in them at intervals corresponding to the spacing of the carrier bars 13, thus permitting the tie bars to be slipped over the struck up ears 20 and moved endwise over the webs 14 into their finally adjusted positions. When the tie bars are thus positioned, the flanges 24 interlock with the struck up ears 20 to prevent vertical or lateral movement of the tie bar relative to the carrier bar.

80 The tie bars 21 are provided with a plurality of pairs of ears 26 which are struck up from the upper web thereof to provide means for securing crossing elements 27 thereto in parallel juxtaposed relation. The crossing elements 27 have inturned bearing flanges 28 which are adapted to underlie the struck up ears 26 of the tie bar to secure the crossing elements in adjusted position. The bearing flanges 28 of the crossing elements have notches 29 at spaced intervals corresponding to the distance between the pairs of struck up ears 20 on carrier bars 13.

95 In the installation of a crossing, the carrier bars 13 are first secured by spikes 12 to the cross ties 11 with corresponding pairs of struck up ears 20 of the several carrier bars in cross alignment. The tie bars are then 100

secured to the carrier bars by so positioning the tie bars with respect to the carrier bars that the struck up ears 20 of the latter register with the notches 25 in the bearing flanges 5 of the tie bars so that the latter may rest upon the carrier bars. The tie bars are then driven longitudinally a short distance to cause the notches 25 to move out of registry with the ears 20 which latter then function 10 to hold the tie bars in position. The several tie bars are so adjusted in position that corresponding pairs of struck up ears 26 of the several tie bars are in cross alignment. Crossing elements 27 are then secured to the 15 tie bars in a manner similar to the securing of the tie bars to the carrier bars.

By providing the carrier bars 13, a tie bar 21 need not be positioned directly above a cross tie 11 as is the case when no carrier bars 20 are used, thereby expediting the installation 25 of a crossing at a place where the cross ties are non-uniformly spaced or are spaced in such a manner as to make it impossible to locate the tie bars in the proper position.

25 Furthermore, by providing carrier bars of different heights it is possible to adapt the crossing to use with rails of correspondingly different heights without necessitating a change in the height of the tie bars or crossing 30 elements.

Although the foregoing description is necessarily of a detailed character in order to completely set forth the invention, it is to be understood that the specific terminology is not intended to be restrictive or confining and it is to be further understood that various rearrangements of parts and modifications of structural detail may be resorted to without departing from the scope or spirit of the 35 invention as herein claimed.

Having thus described the invention, what is claimed and desired to be secured by Letters Patent is:

40 1. In a sheet metal railway grade crossing, the combination with the rails and ties of sheet metal carrier bars extending substantially parallel to the rails and fastened to the ties, sheet metal tie bars extending transversely to said carrier bars and supported 45 thereby, means integral with said carrier bars and tie bars for interlocking the same and preventing relative vertical movement, and crossing elements supported upon said tie bars and fastened thereto in parallel juxtaposed relation to provide a tread surface substantially flush with the tops of the rails.

50 2. In a sheet metal railway grade crossing, the combination with the rails and ties of sheet metal channel shaped carrier bars extending substantially parallel to the rails and fastened to the ties, sheet metal channel shaped tie bars extending transversely to said carrier bars and supported thereby, means integral with said carrier bars and tie bars 55 for interlocking the same and preventing

relative vertical movement, and crossing elements supported upon said tie bars and fastened thereto in parallel juxtaposed relation to provide a tread surface substantially flush with the tops of the rails.

70 3. In a sheet metal railway grade crossing, the combination with the rails and ties of sheet metal channel shaped carrier bars extending substantially parallel to the rails and fastened to the ties, said carrier bars having upper horizontal webs provided with spaced pairs of ears struck up therefrom, the pairs of ears on one carrier bar being aligned laterally with those of another carrier bar, and downwardly extending side walls having 75 horizontal flanges resting on the tops of the ties, sheet metal channel shaped tie bars supported by said carrier bars and extending transversely thereto, said tie bars having downwardly extending side walls provided with horizontal flange portions adapted to cooperate with corresponding laterally aligned struck up ears of said carrier bars to interlock said tie and carrier bars and prevent relative vertical movement, and sheet metal 80 channel shaped crossing elements extending longitudinally of the rails and in juxtaposed relation to provide a tread surface, said crossing 85 elements having means for fastening the same to said tie bars.

90 4. In a sheet metal railway grade crossing, the combination with the rails and ties of sheet metal channel shaped carrier bars extending substantially parallel to the rails and fastened to the ties, said carrier bars having upper horizontal webs provided with spaced pairs of ears struck up therefrom, the pairs of ears on one carrier bar being aligned laterally with those of another carrier bar, and downwardly extending side walls having 95 horizontal flanges resting on the tops of the ties, sheet metal channel shaped tie bars supported by said carrier bars and extending transversely thereto, said tie bars having 100 downwardly extending side walls provided with horizontal flange portions adapted to cooperate with corresponding laterally aligned struck up ears of said carrier bars to interlock said tie and carrier bars and prevent relative vertical movement, said horizontal flange portions having spaced openings 105 therein corresponding to the spacing between said carrier bars to facilitate installation of said tie bars, and sheet metal channel shaped crossing elements extending longitudinally of the rails and in juxtaposed relation to provide a tread surface, said crossing 110 elements having means for fastening the same to said tie bars.

115 5. The combination with a pair of rails supported upon a plurality of ties, of a grade crossing construction comprising carrier bars 120 secured to said ties, tie bars supported by said carrier bars, crossing elements supported by said tie bars, and means for securing said 125 tie bars.

130

bars and elements together, said carrier bars and said crossing elements extending substantially parallel with said rails and said tie bars extending crosswise thereof.

- 5 6. The combination with a pair of rails supported upon a plurality of ties, of a grade crossing construction comprising sheet metal channel shaped carrier bars secured to said ties, sheet metal channel shaped tie bars supported by said carrier bars, sheet metal channel shaped crossing elements supported by said tie bars, and means for securing said bars and elements together, said carrier bars and said crossing elements extending substantially parallel with said rails and said tie bars extending crosswise thereof.

In witness whereof, I have hereunto signed my name at Milwaukee, Wisconsin, this 24th day of March, 1931.
